MULTIPLE SCREW DRIVER

Pierre Picard, Paris, France

Application February 1, 1937, Serial No. 123,472
In France February 21, 1936

2 Claims. (Cl. 145—50)

The present invention has for its object a tool consisting of the combination of several screwdrivers in order that it will serve to operate screws of different sizes, and chiefly adapted for use as a tool which can be readily transported in a kit or a sack, or carried in the pocket.

Its particular feature consists in its reduced size.

The embodiments herein described by way of example in order to set forth the invention are by no means of a limitative nature, and in particular, as to the relative positions of the different blades, their assembling, which is in fact optional, or the case which can be employed as a handle for the screwdrivers and whose use is optional.

In the accompanying drawing, which is given by way of example:

Figs. 1 and 2 show respectively an elevational view and a section on the line $x-y$ of Fig. 1 of a first embodiment of the screwdriver according to the invention.

Fig. 3 shows an elevational view of the screwdriver of Figs. 1 and 2 after removal of the external part.

Figs. 4 and 5 show respectively a front and a side elevational view of a second embodiment in two different positions.

Figs. 6 and 7 show respectively a front and a side elevational view of the screwdriver of Figs. 4 and 5 inserted in a case.

Fig. 8 shows the same screwdriver in its case, but in another position.

Figs. 9 and 10 show respectively an elevational view and a section on the line $s-t$ of Fig. 9 of a modification.

In the embodiment of Figs. 1 and 2, the blade A of the screwdriver having the largest size is cut out in order to contain the blade B of the next smallest size, which is cut out in like manner so as to contain the size C below this latter, and so on. The tool herein represented has only three blades, but owing to the size of the largest screwdriver on the one hand, and to the relative sizes of the different blades, on the other hand, a greater number of blades might be used.

Fig. 2 shows the form of the grooves provided in the blades, which enables the smaller blades to slide within the larger blades in order that they may be assembled in a single tool for transportation. In order to use the largest size, the whole device is used as it is. In order to use the second size, the first is slipped off, thus uncovering the second (Fig. 3) and so on.

In the embodiment of Figs. 4, 5, 6, 7 and 8, the small sides of the blades are flat surfaces which

are perpendicular to the large faces. A spindle G (Fig. 4) connects the three blades D, E and F, and the blades can thus turn about the said spindle. By thus rotating the largest blades on the spindle, the blade to be used can be uncovered, and the blades not in use can be placed at about 90° from the blade in use, and will serve as a right-angled handle for applying the force (Fig. 5).

At the end opposite the screwdriver part, the blades have different lengths, at H, I and J, in order to turn the desired blade with the fingers.

In a more practical arrangement, the said device can be fitted into a flat case K having one or two slots L and M, allowing one or two ends of the spindle G to project, in order to remove the tool from its case (Figs. 6 and 7). The said case serves as a handle for the screwdriver in use, and the projecting ends of the spindle serve as stops in the said slots, in order to withstand the force applied upon the tool. Fig. 8 shows the blade E which is in use, and the blade D is contained in the case, which serves as a handle.

In order to give a greater rigidity to the successive tools, and to provide for larger cut-out parts, thus increasing the number of blades for a given total width of the tool, the recess in a given blade which contains the next blade need not be entirely open, but may comprise a web N, as shown in Figs. 9 and 10, the web being cut off for a part of its length in order to provide for the rotation of the blades on the spindle.

Having now described by invention what I claim as new and desire to secure by Letters Patent is:

1. A tool comprising a plurality of flat screwdrivers having lengths and widths increasing gradually from one screwdriver to another, each screwdriver being provided in the direction of its thickness with a recess flush with at least one flat face of said screwdriver and adapted to receive removably the immediately following smaller screwdriver, the width of each recess being equal to the width of the screwdriver adapted to be engaged in said recess, so that each screwdriver is in contact on the major part of its length by its lateral edges with the lateral edges of its recess, and an axle traversing loosely all of said screwdrivers in a direction substantially parallel to the flat faces of said screwdrivers and disposed between the planes of said flat faces, whereby each screwdriver is adapted to be rotated about said axle by at least 180° with respect to the other screwdrivers.

2. A tool comprising a plurality of flat screwdrivers having widths increasing gradually from

one screwdriver to another, each screwdriver being provided with a recess of such a width as to be adapted to receive removably in said recess between the planes of its opposite flat faces the immediately following smaller screwdriver, an axle traversing all of said screwdrivers in a direction substantially parallel to the flat faces of said screwdrivers and extending beyond the longitudinal edges of the largest screwdriver, and a case adapted to receive said screwdrivers and provided

with two slots adapted to be engaged by the ends of said axle, said ends of said axle serving on the one hand to limit the insertion of the tool into the case in the inoperative position and to remove the tool from said case and on the other hand to support the thrust exerted on the case when this latter is used as a handle in the operative position.
